(57) **CLAIM**

The ornamental design for a mixing apparatus, as shown and described.

DESCRIPTION

FIG. 1 is a right side view of a head portion of a mixing apparatus showing our new design;

FIG. 2 is left side view of thereof;

FIG. 3 is a front view thereof;

FIG. 4 is a rear view thereof;

FIG. 5 is a top view thereof;

FIG. 6 is a bottom view of thereof;

FIG. 7 is a right side view of a second embodiment of a head portion of a mixing apparatus;

FIG. 8 is a left side view of the head portion of FIG. 7;

FIG. 9 is a front view of the head portion of FIG. 7;

FIG. 10 is a rear view of the head portion of FIG. 7;

FIG. 11 is a top view of the head portion of FIG. 7; and,

FIG. 12 is a bottom view of the head portion of FIG. 7

The broken lines shown in the drawings are for illustrative purposes only and form no part of the claimed design.

1 Claim, 12 Drawing Sheets .
